UNITED STATES PATENT OFFICE.

WILLIAM D. BOYCE, OF ST. LOUIS, MISSOURI.

FIRE-BOX.

SPECIFICATION forming part of Letters Patent No. 741,218, dated October 13, 1903.

Application filed March 3, 1902. Serial No. 96,475. (No model.)

To all whom it may concern:

Be it known that I, WILLIAM D. BOYCE, a citizen of the United States, residing at city of St. Louis, State of Missouri, have invented a certain new and useful Improvement in Fire-Boxes, of which the following is a full, clear, and exact description, such as will enable others skilled in the art to which it appertains to make and use the same, reference being had to the accompanying drawings, forming part of this specification, in which—

Figure 1 is a view partly in rear elevation and partly in transverse vertical sectional elevation. Fig. 2 is a longitudinal sectional elevation on the line 2-2 of Fig. 1, and Fig. 3 is a fragmentary sectional plan view on the line 3-3 of Fig. 2.

My invention relates to improvements in fire-boxes for steam-boilers and the like, my object being to so construct a fire-box that the disturbance of the temperature due to firing is greatly reduced and an increased heating-surface is presented.

To these ends and also to improve generally upon devices of the character indicated my invention consists in the various matters hereinafter described and claimed.

Referring now more particularly to the drawings, 1 represents the outer plate of the fire-box, which forms the top and side walls thereof, 8 represents the back plate, and 11 indicates the front plate, said plates 1 and 11 being connected to the boiler shell or casing 12 in the usual manner when the fire-box is used in connection with a boiler, 10 indicating the tubes or flues of such a boiler. Spaced from the said plate 1 are plates 13, which form the outer side and top walls of fire-chambers 6, plates 7 forming the inner side walls of said chambers. The said fire-chambers do not extend the full length of the fire-box leg, whereby water-spaces are left at their front and rear in a manner usual in fire-boxes, and the ends of said fire-chambers are closed by plates 14, which extend only between the walls of the respective fire-chambers, a space communicating with the customary front, rear, and top water-spaces being thus left between the adjacent inner walls 7 of the fire-chambers. Stay-bolts 15 connect the plates forming the outer walls of the fire-box with the plates forming the walls of the fire-cham-

bers, and a separate door 9 opens into each of the fire-chambers 6.

The plates 1 and 13 are supported upon beams 2, which form the outer walls of the ash-pits 3, an intermediate beam or wall 4 serving to separate said ash-pits from each other and each ash-pit being provided with doors 5, whereby the usual single ash-pit is thus in effect separated into chambers, there being a separate ash-pit for each of the fire-chambers 6. The adjacent inner walls 7 of the said fire-chambers are supported upon the said beam 4, and thus form in effect a partition which separates the said two fire-chambers, said walls 7 being spaced apart and connected by stay-bolts 16.

Manifestly, as shown most clearly in Fig. 3, the stay-bolts do not extend over the entire area of the front and back plates of the fire-box, there being a space between said bolts which extends across the space between the walls 7 of the two fire-chambers. In order to brace and strengthen this portion of the said fire-box walls not provided with stay-bolts, I secure vertically pairs of angle-irons 17 to said front and rear plates, and between the adjacent flanges of said angle-irons I secure tie-rods 18 and 19, said tie-rods lying in the space between the walls 7 (or in the plane of said space between the upper stay-bolts 15.) The tie-rods 18, which are at the upper portion of the fire-box, have their forward ends connected to the plate 1 or to the shell of the boiler in any appropriate manner, while the lower tie-rods 19 extend between and are fastened to the sets of angle-irons upon the front and rear plates of the fire-box. In this manner the said fire-box plates are strengthened at the desired places, and are furthermore, firmly braced by the tie-rods, said tie-rods lying in convenient spaces whereby they can be readily positioned.

The fire-box is here shown as applied to a boiler; but it is manifest that it can be employed alone or with any apparatus of any desired type.

As will at once be apparent, the spaced walls 7 of the separate fire-chambers afford an additional heating-surface, thus increasing the heating capacity of the fire-box over a box of the same size provided with the customary single fire-chamber. Furthermore,

each fire-chamber can be independently supplied with fuel, raked, or otherwise attended to, and therefore the fire can be fed or otherwise given attention without, for example, 5 feeding green fuel to the entire fire-box at one time. Thus the disturbance to the temperature of the fire-box is greatly reduced, and by alternately feeding the two fire-chambers it is possible to keep the temperature of 10 the box as a whole almost or quite constant.

I am aware that many minor changes in the construction, arrangement, and combination of the several parts of my device can be made and substituted for those herein shown and 15 described without in the least departing from the nature and principle of my invention.

Having thus described my invention, what I claim as new, and desire to secure by Letters Patent, is—

20 1. In a fire-box, an inclosing shell, an end casing-plate, interior walls spaced apart and dividing said fire-box, said casing end plate extending across the space between said walls, and a tie-rod secured to said end plate and 25 extending in the space between said walls; substantially as described.

2. In a fire-box, an outer plate, inner plates, interior walls connected to said inner plates and dividing the fire-box, said interior walls 30 being spaced apart, stay-bolts connecting said inner and outer plates, there being a space between said bolts in the plane of the space between said walls, a casing end plate extending across the space between said walls 35 and said stay-bolts, and a tie-rod connected to said end plate and extending in the space between said stay-bolts; substantially as described.

3. In a fire-box, an outer end plate, fire- 40 chambers having end plates and provided with inner walls spaced apart, said outer end plate extending across the space between said walls, stay-bolts between said end plates, and a strengthening member upon said outer 45 end plate in the space between said stay-bolts; substantially as described.

4. In a fire-box, an outer end plate, fire- 50 chambers having end plates and provided with inner walls spaced apart, said outer end plate extending across the space between said walls, stay-bolts between said end plates,

a strengthening member upon said outer end plate in the space between said stay-bolts, and a tie-rod connected to said strengthening member; substantially as described. 55

5. In a fire-box, interior fire-chambers having end plates and inner walls spaced apart, an outer end plate at one end of said fire-chambers and extending across the space between said inner walls, stay-bolts between 60 the said outer end plate and the end plates of said fire-chambers, a second outer end plate at the other end of said fire-chambers and extending across the space between said inner walls, stay-bolts between 65 said second outer end plate and the end plates of said fire-chambers, a strengthening member upon each said outer end plate in the space between the said bolts connected thereto, and a tie-rod extending in the space between said walls and 70 having its opposite ends connected to said strengthening members, substantially as described.

6. In a fire-box, end plates, and a tie-rod extending between and connecting said plates; 75 substantially as described.

7. In a fire-box, an outer top plate, outer end plates, interior fire-chambers having top and end plates and provided with inner walls spaced apart, said outer end plates extending across the space between said walls, stay-bolts between said inner and outer end plates and between said inner and outer top plates, there being spaces between said stay-bolts across the space between said inner walls, 85 angle-irons upon said end plates in the spaces between said stay-bolts, a tie-rod connecting the angle-irons upon the respective outer end plates and extending in the space between said inner walls, and a tie-rod secured to the 90 angle-iron upon one of the said outer end plates and extending in the space between the stay-bolts connecting said top plates; substantially as described.

In testimony whereof I hereunto affix my 9 signature, in the presence of two witnesses, this 28th day of February, 1902.

WILLIAM D. BOYCE.
